UNITED STATES PATENT OFFICE.

WILLIAM G. JACKSON, OF MARICOPA, CALIFORNIA.

CASING-TONGS.

1,046,596.

Specification of Letters Patent. Patented Dec. 10, 1912.

Application filed April 22, 1912. Serial No. 692,392.

To all whom it may concern:

Be it known that I, WILLIAM G. JACKSON, a citizen of the United States, residing at Maricopa, in the county of Kern and State 5 of California, have invented new and useful Improvements in Casing-Tongs, of which the following is a specification.

This invention relates to improvements in casing tongs used especially for screwing 10 and unscrewing the separate sections of well casings and pipe lines.

The object of my invention is to provide casing tongs the lever of which can be attached to a reciprocating engine, and which 15 can be very quickly and readily adapted for sections of all sizes.

In the accompanying drawing, Figure 1 is 20 a side elevation of the casing tongs shown in use on a casing section; Fig. 2 is a transverse sectional view of the same.

Referring to the drawing, 1 indicates the main body of the tongs, having upper and lower plane parallel surfaces, and formed with an aperture 2 extending from one side 25 to the other midway between said surfaces.

At a central part of said aperture there is 30 pivoted therein, by a pivot bolt 3 passing entirely through the body, a lever 4, the aperture being made flaring at both ends to permit of the vibration of the lever therein. Pivotally attached to the outer end of the 35 short arm of the lever is a chain 6, preferably of the form common in sprocket chains, that is, consisting of double and single links pivoted together by pivots 7. It differs, however, from the ordinary sprocket chain in that each pivot at one terminal portion of the chain projects a considerable distance on each side of the link.

The body of the tongs is extended on one 40 side of said pivot and is formed with a groove 8 in the outer side of said extension, which is thus in effect formed into two jaws. The inner side of said extension is concaved 45 to fit against the outer surface of the casing 13 and is formed with teeth or corrugations 9. The chain, having been passed around the casing, is inserted in the groove between said jaws and is drawn as tightly around the 50 casing as possible so as to permit one of said extended pivots to be inserted behind two shoulders 11 formed on the body on opposite sides of said groove and directed to-

ward each other, said shoulders, by their abutment against said extended pivots, 55 holding back the chain. As an additional precaution to prevent the chain from coming out of the groove, I form in the sides of said extension, on opposite sides of said groove and behind said shoulders, registering apertures, through which can be passed a spike or pin 12 outside the chain when in position.

Having arranged the casing tongs in the position described, the lever is flexibly connected to an engine having a reciprocating motion. Upon the motion in one direction of the engine and lever, the chain is tightened around the casing and grips it so that it is turned with the 70 lever. Upon the reciprocating motion of the engine in the opposite direction, the lever can be drawn back by hand, so that the chain is then loose around the casing, and can be drawn back to its first position, so 75 that, upon another movement in the first-named direction of the engine, the chain is again tightened and the casing is again turned.

I claim:—

A casing tongs comprising a body portion having an aperture therethrough and an extension having on its outer side a groove forming jaws the inner side being concave and provided with teeth, a lever extending 85 through said aperture and pivoted to said body, a chain in said groove one end of which is attached to said lever, said chain consisting of links and pivots, the pivots extending outside the 90 links, and the body being formed on each side of said groove with shoulders adapted to engage the extended ends of said pivots, said body being also formed with registering apertures, and a pin through said 95 apertures, said apertures being so located that the pin passes outside the chain when in said groove.

In testimony whereof I have hereunto set my hand in the presence of two subscribing 100 witnesses.

WILLIAM G. JACKSON.
